OTHER PUBLICATIONS

Notification issued for counterpart Japanese Application No. 2020-022618, drafted by the Japan Patent Office on Feb. 10, 2021.

Primary Examiner — Christy Nemeth
Assistant Examiner — Leah E Hoeferkamp

(57) **CLAIM**

The ornamental design for an electrical connector, as shown and described.

DESCRIPTION

FIG. 1 is a front, right, bottom perspective view of an electrical connector, showing our new design;

FIG. 2 is a rear, left, top perspective view thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a right side view thereof, with the left side being a mirror image.

The broken lines in the drawings are for the purpose of illustrating portions of the article that form no part of the claimed design.

1 Claim, 7 Drawing Sheets
